UNITED STATES PATENT OFFICE.

NARCISSE N. S. DAUDELIN, OF FALL RIVER, MASSACHUSETTS.

THREAD-BOARD LIFTER.

SPECIFICATION forming part of Letters Patent No. 740,250, dated September 29, 1903.

Application filed December 15, 1902. Serial No. 135,247. (No model.)

To all whom it may concern:

Be it known that I, NARCISSE N. S. DAUDELIN, a citizen of the United States, residing at Fall River, in the county of Bristol and State 5 of Massachusetts, have invented certain new and useful Improvements in Thread-Board Lifters, of which the following is a specification.

My invention relates to a mechanism adapted to automatically raise the thread-board of spinning and twisting frames; and its primary object is to relieve the thread or yarn from the strain which is caused by the limited distance intermediate the ring-traveler 15 and the guide-wire of the thread-board when the ring-rail is at the highest point of the wind, the limited area of play subjecting the thread to abrasion as it passes through the guide-wire and ring-traveler.

20 A further object of this invention is to lessen the swing or ballooning of the thread when the ring-rail is near the bottom of the wind; and a final object is to attain this end by cheap and simple mechanism adapted to adjustment upon the common form of spinning or twisting frame.

25 To the above ends my invention consists in the novel construction and combination of parts hereinafter set forth, and illustrated in the accompanying drawings.

Figure 1 is a transverse section of one side of a spinning-frame, showing the invention in side elevation and the thread-board in normal position; Fig. 2, a similar section of the 35 same, showing the thread-board elevated and the actuating parts in side elevation. Fig. 3 is a vertical section of the thread-board and adjacent parts on line $\alpha\alpha$ of Fig. 1, and Fig.

4 a front elevation of a section of the rock-40 ing-arm rod and attached angle-rod. Fig. 5 is a front elevation of a portion of a spinning-frame, showing the rocking-arm rod connections.

Like figures of reference indicate like parts 45 throughout the views.

This novel mechanism is adapted for use upon the common form of spinning or twisting frames 1, whereon are vertical spindles 2, driven by bands 3 from the drum 4. The 50 ring-rails 5 are vertically movable to feed the thread to the bobbins 6 through the traveler 7. The thread is supplied by the

rolls 8, mounted in the frame 1 above the thread-board 9, and traverses the guide-eyes 10 upon the outer margin of the thread-board. 55 The usual rocker-rail 11 is fixed to the frame below the spindles. Parallel thereto, but in a higher plane longitudinally, reciprocates the usual rocking-arm rod 12, vibrated by the rocking arm or lever 26, fulcrumed to 60 the rock-shaft 27. Also fixed to the rock-shaft is the bar 28, carrying upon one extremity a weight 29 and engaging with its other extremity the lifting rod or poker 30. Fixed to the rocking arm is the chain 31, leading 65 to the builder mechanism. It is in conjunction with these familiar parts that my mechanism is utilized.

To the lower face of the rocker-rail 11 is fixed by bolts 13 or otherwise a rearwardly-projecting supporting-bar 14, upon which is fixed a vertical guide or fork 15, through which passes a lever or link 16, pivoted at one extremity to the supporting-bar and at the other to the link 17, which in turn has its 75 extremity pivoted to the inner end of a forwardly-directed lever 18. The latter lever has fixed to its free end an upwardly-curved finger 19, carrying a terminal roller 20. The lever 18 is pivotally supported at a point in 80 the rear of the finger 19 by a downwardly-directed arm 21, fixed to the frame 1 adjacent the thread-board 9. The latter is hinged upon its inner margin to the frame 1, allowing its outer edge freedom to move upwardly and 85 describe an arc. Upon the bottom of the thread-board and disposed transversely thereto is a metallic strip 22, with upturned marginal flanges, forming a channel in which the roller 20 travels. 90

The rocking-arm rod 12 has fixed to its front face by set-screws 23 a downwardly-projecting angle-arm 24 with longitudinal slots 25 in each end to accommodate the set-screws by means of which the angle-arm 24 may be 95 vertically and longitudinally adjusted and the rise of the thread-board thereby regulated.

The rocking-arm rod, as is well known, vibrates with a longitudinal reciprocating motion, the time consumed in the advance or return of this rod being equal to the time consumed in the rise or fall of the ring-rail. The rod 12 in its advance stroke forces the inclined surface of the angle-arm 24 against

and upon the link 16, forcing the latter downward. This movement is communicated, through the link 17 and the lever 18, to the finger 19, which rises and through the roller 20 elevates the thread-board 19 and its attached guides to correspond with the rise of the ring-rail, the various parts assuming the position shown in Fig. 2. Obviously upon the return movement of the rocking-arm rod 10 the link 16 gradually rises under the action of gravity as the angle-arm retreats and the thread-board approaches its lowest position, as shown in Fig. 1, which position, it will be noted, corresponds with the depression of 15 the ring-rail. An ideal tension is thus automatically obtained upon the threads passing through the guides.

While my device is illustrated as applied to one side of the spinning or twisting frame, 20 it is intended for contemporaneous application to the other side also.

One of the valuable features disclosed is adaptability to frames in common use upon which adjustment is possible without material change of structure.

Having described my invention, what I claim as new, and desire to secure by Letters Patent, is—

1. In a spinning-frame, the combination 30 with the rocking-arm rod of an angle-arm fixed thereto, a hinged thread-board, a rocker-rail, and a series of levers intermediate the latter and the thread-board adapted to be actuated by the contact of the angle-arm.
2. In a spinning-frame, the combination 35 with the rocking-arm rod of an angle-arm fixed thereto, means for adjusting the angle-

arm vertically and longitudinally, a hinged thread-board, a rocker-rail, and a series of levers intermediate the latter and the thread-board adapted to be actuated by the contact of the angle-arm. 40

3. In a spinning-frame, the combination with the rocking-arm rod of an angle-arm fixed thereto, a hinged thread-board and a 45 series of levers below and contacting with the thread-board adapted to be actuated by the contact of the angle-arm.

4. In a spinning-frame, the combination with the rocking-arm rod of an angle-arm 50 fixed thereto, means for adjusting the angle-arm vertically and longitudinally, a hinged thread-board, and a series of levers below and contacting with the thread-board adapted to be actuated by the contact of the angle- 55 arm.

5. In a spinning-frame, the combination with the rocking-arm rod of a projection upon said rod, a hinged thread-board, and a series of levers below and contacting with the thread-board adapted to be actuated by the projection. 60

6. In a spinning or twisting frame, the combination with the rocking-arm rod of an inclined projection upon said rod, hinged 65 thread-boards, and a series of levers below and contacting with the thread-boards adapted to be actuated by the inclined projection.

In testimony whereof I have affixed my signature in presence of two witnesses.

NARCISSE N. S. DAUDELIN.
